[57] CLAIM

The ornamental design for a calibration port adaptor for a gas sensor, as shown.

DESCRIPTION

FIG. 1 is a top and right, front perspective view of a calibration port adaptor for a gas sensor showing my new design;

FIG. 2 is a top plan view thereof;

FIG. 3 is a front elevational view thereof;

FIG. 4 is a left side elevational view thereof;

FIG. 5 is a right side elevational view thereof;

FIG. 6 is a bottom plan view thereof.

FIG. 1

FIG. 2

FIG. 4

FIG. 3

FIG. 5

FIG. 6
